LATCH AND LOCK

Henry George Bedell, Wellington, New Zealand,
assignor to Spiral Locks Limited, Wellington,
New Zealand, a company of New Zealand

Application July 30, 1936, Serial No. 93,408
In New Zealand August 9, 1935

6 Claims. (Cl. 292—198)

This invention relates to latches for doors, gates and the like, and in particular relates to the type of latch wherein a barrel is rotatably mounted on either the hinged or rigid part and having a spirally formed groove in which operates a pin attached to the other part.

According hereto, the cylinder or barrel, having a spiral groove cut therein, is revolvably mounted upon either the hinged or rigid part, and is provided with suitable means by which it may be rotated when required. The other part is provided with a latch stud which is adapted to enter the spiral groove in the barrel at the position to which it is ordinarily brought by a handle. The spiral groove ends in a non-spiral portion, and when the unit is being closed, the stud will revolve the barrel, and the latch stud will then pass into the non-spiral portion. In order to open the hinged part, the handle may be operated so as to revolve the barrel until the stud is clear of the non-spiral portion of the groove and passes into the spiral portion.

The revolvable barrel may have fixed upon its circumference a latch bolt, and upon the operation of the barrel by the travel of the latch stud in the spiral groove, the latch bolt is carried into its closed position, and into engagement with a plate from which projects the latch stud. The movement of the barrel can be reversed and the latch bolt disengaged by operating a handle which revolves the barrel in the reverse direction, means being employed between the barrel and the handle to enable the handle to return to normal position during the time that it is inoperative.

The invention will be described with the aid of the accompanying drawing, wherein:

Figure 1 is a front elevation of the latch applied to a gate, and in a closed position.

Figure 2 is a similar view showing the latch open.

Figure 3 is a plan projected from Figure 1.

Figure 4 is a plan projected from Figure 2.

Figure 5 is a sectional side elevation of the device made up within a latch casing and applied to a door.

Figure 6 is a front elevation of the casing.

Figure 7 is an elevation of the latch plate.

Figure 8 is a plan of the latch with the casing in section.

Figure 9 is a section on line A—A Figure 8, but showing the latch bolt in a disengaged position.

Figure 10 is a part plan showing the latch stud about to engage the barrel.

According to the drawing, more particularly Figures 1 to 4, a barrel 1, having a spiral groove 2 cut therein, is revolvably mounted on a pin 3 projecting from a plate 4, which is fixed on a gate post 5 by screws 6. The groove extends partially around the barrel and ends in a straight or non-spiral portion 2a which is at a position from the beginning of the groove about two-thirds the circumference of the barrel. The barrel 1 is provided with a handle 7 by which it may be rotated on the pin 3, and which provides a weight to retain the barrel by gravity in its normal rest position. A plate 8, having an integral latch stud 9, is fixed to the gate 10 by screws 11, the stud being adapted to enter the spiral groove 20 of the barrel, the normal or rest position thereof being shown in Figures 2 and 4, to which position the barrel is ordinarily brought by the weight of the handle. In such case, when the gate is being closed, the stud 9 will enter the spiral groove as indicated in Figure 4, and will thereby rotate the barrel and the handle with it in the direction of the arrow in Figure 2, until the stud reaches the end of the spiral part of the groove 2 and enters the non-spiral portion 2a. The handle has, during this movement, moved from the position in Figure 2 to the position in Figure 1, i. e. about three-quarters of a turn. In this position the non-spiral end 2a of the groove acts as a stop for the stud 9 and prevents the gate from opening. The handle rests on a lip 12 projecting from the plate 8, and the handle and the lip may be provided with holes 12a through which a padlock may be inserted for locking the gate. In order to open the gate, the handle 7 is lifted so as to rotate the cylinder until the stud 9 is clear of the non-spiral portion 2a and is entered into the spiral portion of the groove. By the movement of the handle being continued to its ordinary pendant position, the gate will be opened, or, once the stud has been entered to the spiral portion of the groove, the pushing of the gate from the exterior will cause the stud to rotate the barrel until the stud is clear of the groove.

In Figures 5 to 10, the device is shown applicable to a door or the like latch, in which case the barrel 13 with its spiral groove 14 ending with the non-spiral portion 14a, is mounted in a casing 15 adapted to be set into a mortise of a door 16. A latch stud 17 (corresponding to stud 9) projects from a plate 18 which is fixed to the door jamb 19, and is normally adapted to enter a transverse slot 20 in the front of the latch casing 15. A member forming a latch bolt 21 pro-

jects from the barrel 14 and, as the barrel rotates, the latch bolt 21 will pass through a vertical slot 22 in the front of the latch casing 15 and into a vertically disposed slot 23 in the plate

- 5 18. On the circumference of the barrel 14, at one end thereof, teeth 24, are formed, the barrel having stub axles 26 rotatable in the latch casing. A wheel 27 with teeth on a part of its circumference meshes with the teeth 24 and is 10 mounted freely on the neck 28 of a socket 29 which is rotatable in the latch casing and which receives the bar 30 for attachment of suitable handles 31. A tongue 32 on the socket 29 works around the gap between the teeth on the wheel 15 27 and limits the movement of the socket 29 by striking a pin 33 in the casing.

In operation, assuming that the door is about to be shut (see Figure 10) and the stud 17 about to enter the transverse slot 20 in the latch casing, 20 then as the closing movement continues, the latch stud 17 will enter the groove 14 in the barrel 13. During the travel of the door to its closed position, the stud 17 will rotate the barrel and cause the latch bolt 21 to move from the position shown 25 in dotted lines in Figure 5 to the position shown in full lines, and to enter the slot 22 in the plate 18. By the time the stud 17 has reached the commencement of the non-spiral portion 14^a, the bolt 21 will have commenced to enter the V shaped slot 23, the non-spiral portion enabling the latch bolt to have a final vertical movement downward into the V shaped slot, resulting in a wedging effect which will retain the door against lateral movement and so obviate rattling. 30 35. In order to disengage the latch, a handle 31 on the bar 30 is rotated in the direction of the arrow in Figure 5, the tongue 32 engaging against a tooth of the toothed wheel 27, which will rotate the barrel 13. Immediately the movement 40 commences, the bolt 21 will move from the slot 23, and when the barrel has been turned sufficiently so that the stud 17 moves from the non-spiral part 14^a to the spiral portion 14, the door will commence to open, and the opening movement 45 continuing, the barrel will be rotated by the latch stud and throw back the latch bolt to the position shown in dotted lines in Figure 5, and in full lines in Figure 9, with the bolt 21 resting on the socket and thus limits further rotation of the 50 wheel 27. The socket 29 is returned to its normal position by means of a coil spring 34 attached to a lug 35 on the socket and anchored to the casing. Thus the handles are normally retained in the same position. The tongue 32 limits the 55 movement of the handle in the direction opposite to that of the arrow by striking the pin 33.

What I claim is:—

1. In a latch, a latch casing with a transverse slot in its face, a barrel rotatably mounted in said 60 latch casing, said barrel having a spiral groove around a portion of its periphery and ending in a non-spiral portion at the other end of said barrel, a latch bolt formed on said barrel, a latch plate, a latch stud attached to said latch plate 65 adapted to enter the transverse slot in the casing and enter the spiral groove and rotate the barrel and latch bolt to engage the latch plate,

and means for manually rotating the barrel to cause the bolt to become disengaged from said latch plate and the latch stud from the spiral groove.

2. In the device as claimed in claim 1, teeth 5 formed on a portion of said barrel, a socket rotatable in said casing, a wheel freely mounted on said socket, said wheel having teeth to engage the teeth on said barrel, a handle bar passing through said socket, means on said socket to 10 rotate said wheel so that the barrel may be rotated to disengage the latch bolt from said latch plate.

3. In the device as claimed in claim 1, teeth 15 formed on a portion of said barrel, a socket rotatable in said casing, a wheel freely mounted on said socket, said wheel having teeth to engage the teeth on said barrel, a handle bar passing through said socket, means on said socket to 20 rotate said wheel so that the barrel may be rotated to disengage the latch bolt from said latch plate, said wheel having a gap between its teeth, a tongue on said socket working in the gap, and a spring to return the socket and the handles to 25 normal position.

4. In the device as claimed in claim 1, said latch bolt being of knife edge form, and the opening in said latch plate of V shape.

5. In a latch device for securing two relatively 30 movable parts, a barrel having a peripheral groove rotatably mounted on one of said parts and a stud on the other part adapted to engage and traverse the groove in said barrel, the groove having first a cam portion of such pitch and shape that the relative movement of the parts when 35 being opened or closed will effect rotation of the barrel and secondly a locking portion contiguous with the cam portion and being such that when the said stud has entered therein, the parts are locked against the normal opening movement 40 until the barrel has been independently rotated, a latch bolt formed on said barrel, said bolt as the barrel is rotated engaging a slot in a latch plate from which said latch stud projects.

6. In a latch device for securing two relatively 45 movable parts, a barrel having a peripheral groove rotatably mounted in one of the parts and a stud on the other part adapted to engage and traverse the groove in said barrel, the groove having first a cam portion of such pitch and 50 shape that the relative movement of the parts when being opened or closed will effect rotation of the barrel and secondly a locking portion contiguous with the cam portion and being such that when the said stud has entered therein, the parts are locked against the normal opening movement 55 until the barrel has been independently rotated, a latch bolt formed on said barrel, a latch casing in which said barrel is rotatably mounted adapted to be fitted to a door, said latch casing having a 60 transverse slot in the front thereof in alignment with the axis of the barrel, said latch stud attached to the door frame so that as the door closes said latch stud will enter the peripheral groove and rotate the barrel thus causing the 65 latch bolt to engage the door frame.

HENRY GEORGE BEDELL.
